UNITED STATES PATENT OFFICE.

ROBERT E. EWING, OF GLOUCESTER CITY, NEW JERSEY, ASSIGNOR TO WELSBACH LIGHT COMPANY, OF GLOUCESTER CITY, NEW JERSEY, A CORPORATION OF NEW JERSEY.

INVERTED INCANDESCENT GAS-LAMP.

1,201,030.

Specification of Letters Patent. Patented Oct. 10, 1916.

Application filed January 12, 1916. Serial No. 71,684.

To all whom it may concern:

Be it known that I, ROBERT E. EWING, a citizen of the United States, residing at Gloucester City, in the county of Camden and State of New Jersey, have invented a new and useful Improvement in Inverted Incandescent Gas-Lamps, of which the following is a full, clear, and exact description, reference being had to the accompanying drawings, forming part of this specification, in which—

Figure 1 is a side elevation partly in section of the device; Fig. 2 is a side elevation of the lower portion of the fixture; Fig. 3 is an elevation of the candle casing; Fig. 4 is a sectional plan view on the line IV—IV of Fig. 3; and Fig. 5 is a detail plan view of the centering ring.

My invention relates to inverted incandescent gas lamps, and particularly to an imitation candle lamp in which the burner mechanism is inclosed within the imitation candle casing.

The object of the invention is to provide a simple, cheap and efficient lamp of this type which may be easily assembled and applied, and is of neat and attractive appearance. The structure is particularly adapted for the C. E-Z incandescent gas lamp, such as shown in the Lyon Patent No. 1,158,249, although it may be used with other inverted cluster burners. It is designed for attachment to the ordinary gas fixture.

In the drawings, 2 represents a coupling the lower portion 3 of which is internally threaded to fit on the ordinary fixture nipple. The upper portion 4 is externally threaded to screw into the lower portion of the valve casing 5, which contains the bypass valve 6, having the projecting operating handle 7. Into the upper end of this valve casing is screwed an extension 8 of the valve casing, which is shown as having two diameters, the upper part being reduced and externally screw threaded so as to receive the base 8^a of the Bunsen mixer tube 9. This base contains the needle valve controlling the jet opening, which needle valve is controlled by the side screw 10, or other adjusting means. The pilot tube 11 extends from the lower valve casing up-

wardly to the pilot tip 12, this tube extending along the valve extension to the Bunsen tube.

To cover the valve casing and form a base for the imitation candle casing, I provide a two-part casing or husk. The lower portion 13 of this shell is slotted into its upper portion at 14 to receive the stem of the valve and has an intermediate hole 15 at one side to give access to the adjusting screw for the pilot tube. The lower end portion of this lower part fits against the lower part of the valve casing and is clamped by the upper shoulder on the coupling for fastening the lamp to the fixture tip. The upper portion 16 of this two-part husk or shell has a projecting lower bead portion which fits within the upper end of the lower portion of this shell and the hole through this upper portion is of such a size as to enable it to be slid down over the Bunsen tube and pilot light tube into its nesting position. Thereafter the imitation candle casing 17 is slid down over the top of the Bunsen tube, its lower end fitting on the recessed inner shoulder of the upper portion of the husk or shell. This candle casing may be made of any suitable material, preferably fiber, externally painted white, or any desirable color, and having two piercings in its side. The upper circular piercing 18 is to give access to the adjusting means for the needle valve, while the lower horizontal slotted portion 19 is to admit air to the Bunsen tube. This air opening is preferably provided with a shutter device 20, having a handle by which it may be operated. This lower slot and air shutter, if the latter is used, are concealed within the upper separable portion of the husk or shell.

To center the imitation candle casing and also to clamp the parts in place on the Bunsen tube, I preferably employ a centering ring 21 having a central hole which fits around the Bunsen tube whose edge portion slips down over the top of the candle casing, this ring having a hole to receive the pilot tube. In this case the clamping means is shown as a separable ring or collar 22 which slips down over the Bunsen tube above the centering ring, has a side slot to

receive the Bunsen tube and is clamped to the Bunsen tube by any suitable means, such as the clamp screws 23.

Where the C. E-Z small limp mantle burner is to be used on this lamp, the burner tube 24 for supporting the mantles is slipped on the top of the Bunsen tube, this fixture portion being the same as that now in general use by the Welsbach Company under the patent of Lyon above mentioned, and others.

The parts above the candle casing may be concealed by a shade or globe which may be supported on the top of the C. E-Z burner.

15 If glassware is to be used, I preferably provide the globe holder 25 whose central portion is adapted to engage and snap over the centering ring previously described. This globe holder may have any suitable means 20 for holding a globe 26 which will project up around the burners and mantles, and conceal the same.

The advantages of my invention will be obvious to those skilled in the art. It provides an effective imitation candle fixture which is of attractive appearance, the burner mechanism being hidden and the lamp being capable of easy and quick attachment to existing fixtures. The lamp may be sold 30 in assembled form ready to be screwed on the ordinary fixture. The lower husk or shell provides for the projecting of the operating stem or handle through it; while, at the same time, the upper portion of this shell is not mutilated and is a complete ring. The air enters the candle casing within the upper part of this husk or shell and thence travels up to the Bunsen inlets in the upper portion of the casing where the projecting 35 screw gives capacity for adjustment of the gas jet outlet. The pilot tube is hidden within the candle casing and the burner parts are concealed within the glassware or shade device.

40 45 Many changes may be made in the form and arrangement of the parts without departing from my invention.

I claim:

1. In an imitation candle fixture for incandescent gas lamps, a Bunsen tube, an imitation candle casing surrounding the Bunsen tube and having an air opening through the side portion thereof, a lower husk member for supporting said casing and concealing said opening, and a shutter within the casing for varying the size of said opening; substantially as described.

2. In an imitation candle fixture for incandescent gas lamps, a candle casing arranged to inclose the burner parts and a portion of the Bunsen tube, a needle valve having adjusting means projecting through said casing, the casing having an air opening in its lower portion, and a husk inclosing the 60 65 air opening; substantially as described.

3. In an imitation candle fixture for incandescent gas lamps, a candle casing inclosing the burner mechanism, and a lower husk made in separable parts, one of said parts having a stem projecting through it for controlling the gas supply; substantially as described.

4. In an imitation candle fixture for incandescent gas lamps, a gas valve casing having a surrounding husk made in a plurality of divided parts, the valve stem projecting through one of said parts, and a coupling for clamping the lower husk part against the lower end of the casing; substantially as described.

5. In an imitation candle fixture for incandescent gas lamps, a gas valve casing having a surrounding husk made in a plurality of divided parts, the valve stem projecting through one of said parts, and a coupling for clamping the lower husk part against the lower end of the casing, the lower portion of the husk having an opening giving access to the pilot adjustment; substantially as described.

6. In an imitation candle fixture for incandescent gas lamps, a Bunsen tube, a valve casing, a husk comprising upper and lower members, the lower husk member being clamped against the lower part of the valve casing and inclosing the same, the upper husk member being adapted to be inserted from the other end of the lamp over the Bunsen tube into seating position with the lower husk part, a support for the top of said casing surrounding the Bunsen tube and engaging the casing, and means for holding said support in position on the Bunsen tube and the casing; substantially as described.

7. In an imitation candle fixture for incandescent gas lamps, a valve casing having a husk made in a plurality of parts, the lower husk part being clamped against the lower part of the casing, and the upper husk part being capable of nesting from the other end of the lamp into seating position with the lower husk part, the lower husk part having an upper slot at one side to receive the valve stem; substantially as described.

8. In an imitation candle fixture for incandescent gas lamps, a Bunsen tube, a candle casing surrounding a portion of the Bunsen tube, a support for the top of said casing surrounding the Bunsen tube and arranged to retain the candle casing in position, means for retaining said support in position on the Bunsen tube, a burner head supported on the upper end of the Bunsen tube and arranged to support a mantle, and a pilot light tube within said casing and extending above the support for the top of the casing to a point adjacent to a mantle supported on the burner head; substantially as described.

9. An imitation candle fixture for incandescent lamps, comprising a valve casing, a Bunsen tube, a husk having upper and lower members, the lower member being secured to the valve casing, the upper member being nested in the lower member, said husk being arranged to conceal the valve casing, a candle casing supported on the husk and surrounding a portion of the Bunsen tube, a support for the top of the candle casing surrounding the Bunsen tube and engaging the top of the candle casing, and a collar secured to the Bunsen tube and arranged to retain the support, the candle casing and the husk member in position; substantially as described. 10. An imitation candle fixture for incandescent gas lamps, comprising a valve casing, a Bunsen tube, an imitation candle casing surrounding the Bunsen tube, a burner head supported on the upper end of the Bunsen tube and arranged to support mantles, and a pilot tube within the casing, said pilot tube extending to a point adjacent to the mantles, substantially as described. 11. In an imitation candle fixture for incandescent lamps, said lamp comprising a valve casing and a mixing tube, an imitation candle casing surrounding the valve casing and a portion of the mixing tube, said candle casing having a husk member at its lower end, means for clamping said husk member against the lower end of the valve casing, and means surrounding the Bunsen tube for clamping the upper portion of the candle casing in position on the lamp; substantially as described.

In testimony whereof, I have hereunto set my hand.

ROBERT E. EWING.
